UNITED STATES PATENT OFFICE.

MAX RÜPING, OF MUNICH, GERMANY, ASSIGNOR TO DÜBELWERKE G. M. B. H., OF BERLIN, GERMANY.

DRIVER FOR DRIVING THIN-WALLED DOWELS INTO RAILWAY SLEEPERS.

Application filed November 25, 1924, Serial No. 752,223, and in Germany January 25, 1924.

This invention relates to a driver designed for driving thin-walled dowels into railway sleepers or ties.

In a certain type of railway tracks the rails are supported on transversely positioned sleepers or ties to which they are attached by means of screws and base plates. Each screw is generally passed through a hole in the base plate and is arranged in 5 threaded engagement with the wood tie, the head of the screw serving to anchor the rail on the base plate. After a certain time the screws become loosened in the ties by reason of vibrations caused by the train traveling 10 on the track and this applies particularly to curves in the track. The screws finally become so loose that they are easily pulled out and it is in order to be able to maintain such ties in use that it has long been the practice 15 to reinforce or fill the widened holes.

Since a screw of the dimensions used for attaching the rails cannot be screwed in the solid wood, but requires a preliminarily bored hole whose diameter is smaller than 20 that of the screw bolt shank, the blocks or 25 plugs inserted in the widened hole must be provided with a hole of this kind. Such preliminarily bored plugs are called in Germany, dowels. The holes cannot be conveniently bored after the insertion of the 30 plugs as this would not ensure the hole being bored at the exact center of the dowel nor are the plugs accessible along the track.

Heretofore dowels with relatively strong 35 walls have been used in filling the widened holes as they must be hammered in or else the dowels have been provided with threads and screwed in the holes. In order to drive such heavy dowels in the holes it is necessary to widen the holes in the ties by further 40 boring. This requires much time and material as ties which have been in service for a number of years have holes filled with sand and the like, soon dulling the drill and requiring re-sharpening thereof. It is thus of 45 importance to avoid having to drill the holes wider in the ties and to make use of thin-walled dowels which, however, if used without a special auxiliary means, when driven in 50 the hole of the tie would be injured.

It is the primary aim and object of this invention therefore to provide a driver for driving thin-walled dowels into the holes of ties, the driver having a mandrel which is 55 adapted to be inserted into the bore of the

dowel, said mandrel serving to prevent the crushing of the dowel when the same has been driven in the sleeper through the hole of the base plate.

It is an additional and equally important 60 object of the invention to provide abutting surfaces on the mandrel which considering a single radial plane are spaced longitudinally thereon to ensure of the shocks incident to the driving thereof being distributed 65 throughout the length of the dowel.

Other objects as well as the nature, characteristic features and scope of the invention will be more readily apparent from the following description taken in connection with 70 the accompanying drawings and pointed out in the claims forming a part of the specification.

The invention is clearly illustrated in the accompanying drawings, in which the figure 75 is an elevational view partly in section showing the improved driver with a dowel on the mandrel thereof at the time the dowel is finally anchored in the tie.

Referring now, more particularly, to the 80 accompanying drawings the driver is composed of two parts, namely, a top part *a* reduced to provide a shoulder and a depending mandrel *i* the latter being provided in turn with abutting surfaces in the form of 85 spiral teeth which are adapted to engage the inner bore of the dowel *k*. It is to be noted that these abutting surfaces, which considering a single radial plane are spaced longitudinally on said mandrel. The top part *a* 90 is receivable within a socket *b* in the driven member *c*, a bolt *d* acting to connect the top part *a* to the driven member *c* the bolt being detachably held in position by means of a 95 cotter *f*. A rod *m* inserted through the transverse bore in the driven member *c* serves as a handle for the driver.

The most important element of the tool is the mandrel *i* which is inserted in the bore of the thin-walled dowel for preventing its 100 injury or collapse on being driven in during which operation the annular front surface of the member *a* projecting laterally from the mandrel when struck transmits the blow to the front surface of the dowel while the 105 mandrel *i* placed in the bore of the dowel *k* prevents injury thereto. It has been shown that with the use of a smooth mandrel *i* the dowel will still be injured in being driven in because the pressure or force ex- 110

ereted on the upper part or end of the dowel through the top part *a* is too great and could not be withstood by the thin wood walls. However when a threaded end is provided for the mandrel as shown in the drawing having downwardly directed relatively large front end surfaces, the dowel is never damaged.

The effect of the thread is that on driving 10 in the lower end of the dowel the wood is compressed inwardly and is thereby forced into the threads of the mandrel *i*. The lower end is driven in with relative ease as the adhesion of this short end to the walls of the 15 hole is relatively slight by reason of the shortness of this end.

As soon as the thread *i* engages in the wood of the dowel the further insertion of the dowel takes place not only through the 20 action of the force exerted by the end surface of the top part *a* on the upper front or end surface of the dowel but also simultaneously through the effect of the thread which now draws the lower end of the dowel into 25 the hole or in other words the impact of the blows is no longer transmitted only to the upper front end of the dowel, but through the end of the screw thread on the 30 wood of the lower dowel portion at the same time. Inasmuch as the result of this action the impact force is distributed over a larger surface and the largest part of this surface is at the lower end of the dowel, which is 35 protected from injury by the walls of the hole in the tie, any damage is completely precluded by the use of the new tool.

It is repeated that by reason of the use of the new tool, the dowel may be made with extremely thin walls and as a result it is 40 not necessary to enlarge the widened holes in the ties before driving in the dowel, thus saving labor.

After the dowel has been driven in by means of the mandrel, the top part or member *a* is rotated and therewith the mandrel *i* which is carried with the latter. In this rotation the steep pitch of the thread of the mandrel engaged in the wood of the dowel screws the mandrel out of the dowel so that 45 the mandrel is released from the dowel wood after a few turns and the member or top part *a* drawn out upwardly.

After the mandrel has been withdrawn 50 from the dowel and the screw bolt by means of which the rails are fastened on the tie is again screwed in the tie, that is in the hole of the dowel *k* as the dowel is inserted in the hole of the tie for the reception and retention of the screw bolt.

Another point to be noted is that the base 60 plate which is inserted between the rail foot *o* and the tie *n* is generally maintained by three screws. In other dowelling methods the base plate in order to permit dowelling 65 must be removed from its position in order

to make the hole in the tie accessible therefor. If at the point of attachment only one of the three screw bolts has become loosened, the other two which pass through the same plate must be loosened or removed; when again screwed in they never have the same solid retention in the wood and they also must be dowelled thus an increased expense of labor and material.

With the use of the new tool this defect 75 can be eliminated when the lower part *a* is made so thin as to pass through the hole in the plate *g* and the dowel *k* made so thin that it can be passed through the hole in the plate *g*. Then, when one of the screws become loosened the other may be left in place and also the plate left in place, the dowelling being done through the hole in the plate. In this connection it is to be understood that the plate is by no means nailed 80 fast to the tie by means of the dowel but the latter penetrates entirely through the plate. After driving in the dowel no part thereof is in the hole of the plate; the dowel serving solely for the reception of the screw 85 bolt the head of which forces the foot *o* of the rail against the plate *g* and the latter is forced against the tie *n*.

Even when all of the screw bolts of one 90 plate become loose the dowelling can be done without removing the plate, which is an important advantage because, as long as the plates are in position below the rails the train can travel on the track without danger as the rails are still supported by other ties; 95 however, if the plate is removed the rails are likely to bend to a great degree and accidents may occur. The dowelling operation can thus be carried out without interrupting the operation of trains over the 100 track.

It is believed in view of the foregoing 105 that a further detailed description of the operation of the invention is entirely unnecessary. Likewise it is believed that the 110 advantages of the invention will be readily apparent.

Having thus fully described the invention what is claimed as new and desired to be 115 secured by Letters Patent is:—

1. A driver designed for the driving in of thin-walled dowels into railway sleepers comprising a top part, a reduced mandrel depending from the top part and forming a shoulder, and abutting surfaces which, considering a single radial plane, are spaced longitudinally on said mandrel.

2. A driver for driving thin-walled wooden dowels comprising an enlarged top part and a reduced mandrel, thereby providing a shoulder at the junction with the top part, and the mandrel having a high pitched thread cut therein.

3. A driver for driving thin-walled wooden dowels comprising an enlarged top 130

part and a reduced mandrel, thereby providing a shoulder at the junction with the top part, and the mandrel having a high pitched thread cut in the lower portion 5 thereof.

4. A driver for driving thin-walled wooden dowels, including an enlarged top part, a reduced mandrel depending from said top part and forming a shoulder at the 10 juncture with the top part, abutting surfaces which, considering a single radial plane, are spaced longitudinally on said mandrel, and the top part of the driver having a diameter such that the shoulder will always contact

with the upper edge of the dowel during the 15 driving operation.

5. A driver in accordance with claim 2, wherein the deep pitched thread is multiple so that notwithstanding the depth of the pitch the threads lie close to each other. 20

6. A driver in accordance with claim 2, wherein the lower flank of the thread is vertical and the upper flank oblique with respect to the axis of the mandrel.

In testimony whereof I have signed my 25 name to this specification.

MAX RÜPING
